UNITED STATES PATENT OFFICE.

JOHN TURKE AND BENJAMIN F. REIL, OF BOSTON, MASSACHUSETTS.

CAR-DOOR LOCK.

1,096,770.

Specification of Letters Patent. Patented May 12, 1914.

Application filed February 7, 1914. Serial No. 817,255.

To all whom it may concern:

Be it known that we, JOHN TURKE and BENJAMIN F. REIL, citizens of the United States, residing at Jamaica Plain, Boston, in the county of Suffolk and State of Massachusetts, have invented new and useful Improvements in Car-Door Locks, of which the following is a specification.

This invention relates to improvements in car door locks, especially locks for the sliding doors of freight cars, the object of the invention being to provide an improved locking apparatus of this kind embodying a catch carried by the car door, a hasp to engage the catch and secure the door in closed position, an operating cam for the hasp to enable the latter to be manually moved to disengaging position, and a controlling lock to secure the cam against movement when the car door is locked and hence prevent the hasp and cam from being manually operated to release the car door until after the lock has been opened by an authorized person who knows the combination thereof, thus avoiding the use of car door seals, preventing car doors from being surreptitiously opened by unauthorized persons, preventing the stealing of the articles from the cars and enabling economies to be effected in the operation of the freight service of railroads.

The invention consists in the construction, combination and arrangement of devices hereinafter described and claimed.

In the accompanying drawings:—Figure 1 is a side elevation of a portion of a side of a freight car provided with a sliding door with locking means for the door constructed in accordance with our invention, the door being shown in partly open position and the cover for the panel in which the combination lock and the manually operated handle are located being shown as in raised position, disclosing the combination lock and said handle. Fig. 2 is a detail horizontal 45 sectional view of the same on the plane indicated by the line $a-a$ of Fig. 1 and showing the door in closed and lowered position. Fig. 3 is an elevation from the interior of the car and partly a vertical sectional view, 50 showing the door in locked position. Fig. 4 is a detail, similar view, showing the door in unlocked position.

For the purposes of this specification a wall or side of a freight car is indicated at 55 1, with the door opening 2 and the usual sliding door 3 for covering and uncovering

said door opening. In accordance with our invention we provide the door, on its inner side, with a catch 4 which is horizontally arranged, is spaced from and parallel with the inner side of the door, projects somewhat beyond one edge of the door and has a rectangular opening 5. This catch is secured to a right angled bracket 6 which is secured by suitable bolts 7 to the door, the heads of the bolts being preferably countersunk in the door and being preferably of frusto-conical shape so that they cannot be turned from the outer side by a wrench or the like device to disengage the bracket and the catch from the door. The jamb 8 against which the door closes is provided with a horizontal transverse opening 9 to receive the catch 4 and is also provided with a vertical slot 10 below and the upper end of which communicates with said opening 9. On the inner side of the car wall or side 1 is a panel 11 which covers an opening 12 in the wall and is secured to the wall by bolts or other suitable devices 13. This panel is provided with a pivot bolt 14 which extends therethrough and on the inner side of the panel is a hasp 15 which is pivotally mounted on the bolt 14 and extends into the opening 19 and slot 10 and is provided at its free end with an upstanding shoulder 16 and an inclined cam face 17, the outer end or free end of the hasp being substantially triangular in form. A spring 18 is employed to move the free end of the hasp upwardly so as to cause the shoulder of the hasp to engage in the opening of the catch 4 when the door is moved to closed position, which will be understood, the cam face of and of the hasp causing it to be depressed against the tension of the spring as the front end of the catch moves over the shoulder, the spring then moving the hasp upwardly so as to engage its shoulder in the opening 5. The spring 18 is here shown as a coiled spring having its lower end secured to the hasp as at 19 and its upper end secured as at 20.

To operate the hasp and enable it to be disengaged from the catch we provide a stub shaft 21 which is mounted in a bearing opening in the panel 11 and is provided at its outer end with a cross handle 22. To the inner end of the stub shaft is secured an eccentric cam 23 which bears on the upper side of the hasp. The cam when in one position permitting the hasp to raise and when in another position, at an angle of

about 90° from its first position, causing the hasp to be moved downwardly to disengage its shoulder from the opening in the door catch. This cam is provided on one side at 5 a point diametrically opposite its curved cam face 24 with a projection 25 on opposite sides of which shoulders 26—27 are formed. Stops 28—29 are provided, the former to engage the projection 25 when the cam is in 10 initial position with the hasp elevated or locked and the stop 29 to engage the projection 25 when the hasp is depressed to release the door catch. The cam is manually operated by means of the stub shaft and 15 the cross handle. We also provide a controlling lock 30 for securing or releasing the cam to prevent or permit the latter to be operated. This controlling lock is here shown as a combination lock secured on the 20 inner side of the panel 11 and with its knob and disk exposed on the outer side of the panel and in the box 31 which is formed on the outer side of the wall, around the opening 12 and within which box the cross handle is also arranged. The bolt 32 of the lock 25 is pivotally connected to a detent plunger 33 as at 34, the said detent plunger being adapted to engage the notch 26 of the cam when the latter is in closed position and being arranged to operate in a guide 35. A cover 36 is provided for the box 31 and is here shown as hinged as at 37 so that it may be swung to closed position to protect the lock knob and disk and also the handle 30 of the manually operated cam and a suitable fastening 38 is also provided for this cover.

When the door is moved to closed position it becomes automatically locked by the engagement of the hasp with the catch as hereinbefore described. In order to unlock the

door, an authorized person who knows the combination of the lock, must first operate the lock so as to cause its bolt to be retracted, such movement of the bolt causing the detent plunger 33 to disengage the notch 26 of the cam. The cam is then turned manually by the stub shaft and cross handle so as to depress the hasp and disengage the latter from the catch. The door may be then readily opened. 45

In practice, when a combination lock is employed, directions for operating the combination lock will be given on the way bill so that the agent at the station to which the 55 freight is destined will know how to operate the combination lock and hence be enabled to open the car door.

Within the scope of our invention any suitable kind of lock may be employed for 60 controlling the operating cam.

Having thus described our invention, we claim:

In a lock of the class described, a door carried catch, a hasp to engage the catch, 65 a cam to operate the hasp and having a projection, manually actuated means to operate the cam and forming the pivot thereof, stops coacting with the projection of the cam to limit the movement of said cam and 70 a controlling lock independent of the cam operating means and including a movable bolt adapted to engage and disengage the projection of the cam to lock or release the latter. 75

In testimony whereof we affix our signatures in presence of two witnesses.

JOHN TURKE.
